UNITED STATES PATENT OFFICE.

OLIVER FISHER, OF SLOAN, IOWA.

MAIL DELIVERER AND RECEIVER.

No. 873,527.

Specification of Letters Patent.

Patented Dec. 10, 1907.

Application filed September 4, 1907. Serial No. 391,332.

To all whom it may concern:

Be it known that I, OLIVER FISHER, a citizen of the United States, and a resident of Sloan, in the county of Woodbury and State 5 of Iowa, have invented new and useful Improvements in Mail Deliverers and Receivers, of which the following is a full, clear, and exact description.

This invention has reference to improvements in mail deliverers and receivers which 10 are adapted to be used in either fixed or movable positions as at stations or on trains, as desired.

An object of the invention is to provide a 15 delivering device embodying a collapsible frame which is held open by the mail pouch, and automatically folds or closes up in a substantially vertical plane as the bag is removed, thus carrying the delivering mechanism out 20 of the danger zone.

A further object of the invention is to provide a mail receiving device which will securely grasp the pouch without undue shock, and hold it as the receiving mechanism swings 25 to a removed and inoperative position under the force of impact; also to provide for the reversal of the receiving mechanism, whereby it is adapted to catch the pouch from either direction.

30 Reference is to be had to the accompanying drawings forming a part of this specification, in which similar characters of reference indicate corresponding parts in all the views.

Figure 1 is a side elevation of my invention 35 as applied to a post, which is usually located at the station, showing the mail deliverer in extended operative position with the mail pouch in place; also showing in dotted outline, the delivering mechanism collapsed 40 when the pouch is removed; Fig. 2 is a plan of the mail receiver with the parts of the receiver disposed in operative position preparatory to catching the pouch, and the position of the parts immediately after the pouch is 45 caught, in dotted outline. Fig. 3 is a plan of the mail receiver when thrown to an inoperative position, and also showing it in dotted outline in a like position when it is reversed; Fig. 4 is a fragmentary sectional view on an 50 enlarged scale at the point where the mail receiver is attached to the post; Fig. 5 is a detail view of a latching-plate forming an element of the construction; Fig. 6 is a section on the line 6—6 of Fig. 2; Fig. 7 is a detail of 55 construction in section of the mail receiver; Fig. 8 is a side view on an enlarged scale of

the upper suspending device for the mail pouch of the mail deliverer; and Fig. 9 is a fragmentary view of the mail deliverer in plan.

To a post or other suitable support 10, which is usually located at the station, I have shown my improved mail deliverer attached, the same consisting of a collapsible frame comprising the arms 11 and 12, respectively, 60 arranged in a vertical plane at the top and bottom of the device and connected together at their inner ends by a substantially vertically arranged link 13, and at points therebeyond by cross-bars 14 and 15, respectively. 65

The link 13 is provided with a socket 16 which is rigidly fixed at a suitable point of its length and embraces the angularly-turned end of a stud 17 carried by the supporting post. Also connecting the collapsible frame and the post is a shoe 18 which is fulcrumed on the extended ends of the pivot connecting the arm 11 and link 13 together, the said shoe being journaled on a bolt or other vertical axis passing into the 80 top of the post, and being provided with a rearwardly directed fork between which is journaled a sheave 19. A line 20, attached to the arm 11 and passing over the sheave, carries at its free end a counter-weight 21 85 which serves to break the fall of the frame and thus prevent shock when the frame collapses.

As shown in Fig. 2, the inner portion of 90 the upper arm 11 is composed of two plates which are rigidly connected to and spaced apart by the outer portion of the arm, forming a slot for receiving the upper ends of the link 13 and cross-bar 15.

The arm 12 is jointed at a point intermediate its length, as shown in detail in Fig. 9, this being preferably accomplished by bifurcating one portion of the arm as shown in said figure. The arm 12 is also provided with a side-bar 22 having a projection 23 at 100 its forward extremity overhanging the outer portion of the arm and adapted to contact therewith when the jointed sections of the arm are brought into alinement. The side-bar 22 is the only portion of the arm 12 which 105 connects with the link 13, and the inner jointed portion of this arm is the only part thereof which connects with the cross-bar 14. The lower extremity of the cross-bar 15 passes between the cross-bar 22 and the 110 inner jointed portion of the arm 12, and is pivotally connected to both. By this con-

struction when the free ends of the arms are unsupported or disconnected from each other, the frame will collapse in a substantially vertical plane and fold up in the manner as illustrated in dotted outline in Fig. 1, thus carrying the frame to a removed position and out of the danger zone.

For attaching the opposite ends of the mail pouch to the arms 11 and 12, the extremities of each are respectively provided with fingers 24 and 25, the said fingers being connected by vertically arranged pivots 26, the heads of which are engaged and drawn inwardly by springs 27.

15 The outer end of the finger 24 carries a roller 28, against the upper periphery of which is firmly pressed by a spring 29 a catch 30, the latter being fulcrumed to the outer end of the spring and adapted to be carried outwardly to the dotted position shown in Fig. 8, when the pouch is forcibly removed. The finger 25 is provided with a flat spring 31 which engages directly with the handle or other fastening of the pouch.

20 From the construction it is seen that the receiver has a limited lateral pivotal movement by reason of the connections 16 and 18 with the post or other support 10, which permits of the pouch being swept from between the arms without substantial shock. It will also be observed that the pouch when held between the arms will be under slight tension by reason of the action of the springs 27 on the pivot bolts 26 of the fingers 24 and 25, respectively. This force tending to draw the arms 11 and 12 together will keep the collapsible frame fully extended and thereby hold the bag in the path of the mail catcher carried by the train.

25 40 Attached to the post 10, preferably below the mail deliverer, is my improved mail receiver, comprising a frame which is composed of an off-set lever 32, the outer end of which is bifurcated or composed of two plates spaced apart, as shown in Fig. 6, which receive and are pivoted to bars 33 and 34 arranged in substantial parallelism and pivoted at their outer ends to an arm 35; a like arm 36 having a bifurcated inner end pivoted to the bar 33, and slidably receiving the bar 34 serves in connection with the arm 35 to automatically embrace the pouch when it is forcibly projected therebetween.

45 As shown in Fig. 2, the arm 36 is extended beyond the bar 33 where it is connected with the arm 34 through the intermediary of a link 37. The bolt or other device which connects the link 37 and arm 36 also passes through a plate 38 arranged between them and shown in detail in Fig. 7; the said plate being composed of two thicknesses of metal, one of which is curved about the outer end of the other, forming a guide-way which receives a spring-arm 39, the said arm being 50 pivoted to the link 37 and having a hooked

outer end with an adjacent operating handle 40. This hooked end of the arm is adapted to engage within a notch in the lever 32 and provide a latch for preventing the accidental separation of the arms when in embrace 70 with the pouch.

The connection between the post 10 and the mail receiving frame is effected by pivoting the inner end of the off-set lever 32 between the ears of a bearing-plate 41 which is 75 adapted to swing in a vertical plane on a pivot bolt 42, the latter also passing through a fixed bearing-plate 43 arranged in contact with the plate 41 at the rear of the post and a plate 44 at the front of the post having extended portions provided with angularly-turned extremities 45, the latter being adapted to alternately engage, as the receiver is reversed, with the hooked end of a locking lever 46 pivoted to the lever 32, as shown in 80 detail in Fig. 6. The lever 46 is extended into the path of the inner end of the arm 36 which operates to disengage the latching or locking end of the lever from one of the projections 45 at about the same time the spring 90 arm 39 engages the lever 32, and locks the arms in embrace with the pouch; thereafter permitting the frame, which is at this time in the dotted position shown in Fig. 2, swinging in its entirety on the pivot connecting the 95 lever 32 with the plate 41, thus carrying the entire mechanism to the rear of the post, as shown in Fig. 3.

As best shown in Fig. 4, the bearing-plates 41 and 43 are bifurcated at both ends and a locking lever 47 is pivoted in the bifurcation of the plate 41 at one end. This lever 47 is provided with a pin 48 which is adapted to be swung to the inner face of the plate 43 when the bifurcations in the two bearing-plates align, thus locking the plate 41 against pivotal movement. When the receiving frame is swung to the front of the post as when placing it in operative position, as shown in Fig. 2, the off-set portion of the lever 32 passes within the bifurcations of the plates 41 and 43, not engaged by the locking lever 47, which provides a stop for the frame when in the required forward position. In shifting the receiving mechanism to catch 115 pouches moving in the opposite direction, the frame is thrown to the rear of the post and the locking lever disengaged from the plate 43, after which the inner frame is revolved one hundred and eighty degrees on 120 the bolt 42 which brings the locking lever 47 into register with the bifurcation in the opposite end of the plate 43. The frame when now swung to the front of the post will have the arms directed in the opposite direction. 125

I have shown my improved mail deliverer and receiver as applied to a post for the convenience of illustrating the construction and its operation. It is, however, apparent that with slight modification the receiving and de- 130

livering devices may be also applied to the mail car or other parts of the train and coast with my improved deliverer and receiver, respectively, carried by the post, and operate

5 to deliver and discharge pouches to and from the train while the latter is in motion.

The mail deliverer and receiver as shown and described while being the preferred practical embodiment of my invention may obviously be modified in its detailed construction, and I consider myself entitled to such changes as fall within the scope of the annexed claims.

Having thus described my invention, I claim as new and desire to secure by Letters Patent:

1. In a mail pouch deliverer, a frame adapted to be held in an extended position by the pouch, means adapting said frame to 20 collapse in a substantially vertical plane when the pouch is removed, and counter-balancing means for breaking the fall of the said frame when it collapses.

2. In a mail pouch deliverer, arms for holding the pouch, one of which is composed of two jointed sections and a side-bar having a projection overhanging one of said sections, cross-bars connecting said arms together, and means for pivotally supporting said 30 arms.

3. In a mail pouch deliverer, arms for supporting the pouch, cross-bars and a link connecting said arms together, and means carried by the link for pivotally attaching the 35 arms.

4. In a mail pouch deliverer, arms, one of which is composed of two jointed sections and a side-bar having a projection overhanging one of said sections, a bar pivoted to the 40 other of said sections and to the other arm, a second bar pivoted to the side-bar and to one of said sections at one end and pivoted at its opposite end to the other arm, a link connecting the last-named arm with the said 45 bar, and means carried by the link for pivotally attaching the arm.

5. In a mail pouch deliverer, a finger to which the pouch is adapted to be applied having a roller journaled in its outer end, a 50 spring attached to said finger, and a latch pivoted in the free end of said spring and normally forced into contact with the circumference of said roller.

6. In a mail pouch deliverer, arms arranged in a substantially vertical plane for supporting the pouch, one of said arms being composed of two sections jointed together and a side-bar, a link and cross-bars connecting said arms together, and means for 55 pivotally connecting said arms, cross-bars and link, whereby they are adapted to swing laterally.

7. In a mail pouch receiver, a swinging frame having arms for embracing the pouch, 60 means for locking the frame against swing-

ing movement, means for locking the arms as they close about the pouch, and means for thereafter automatically unlocking the frame.

8. In a mail pouch receiver, a support, a frame pivoted to said support having arms for embracing the pouch, means adapting said frame to swing in a substantially horizontal plane from the front to the rear of the support as the arms embrace the pouch, 75 and means for revolving said frame in a vertical plane at the rear of the support, whereby the arms may be disposed at the front thereof in either direction.

9. In a mail pouch receiver, a support, a frame pivoted to said support having arms for embracing the pouch, means adapting said frame to swing in a substantially horizontal plane from the front to the rear of the support as the arms embrace the pouch, 80 means for revolving said frame in a vertical plane at the rear of the support, whereby the arms may be disposed at the front thereof in either direction, and means for locking the frame at either side of the support with the 85 arms in operative position.

10. In a mail pouch receiver, a pivotally mounted frame having arms for embracing the pouch, means for locking the frame when the arms are disposed in operative position, 95 means for automatically locking the arms as they embrace the pouch, and means for thereafter automatically unlocking the frame, whereby it is adapted to swing on its pivot.

11. In a mail pouch receiver, a pivotally mounted frame having arms for embracing the pouch, means for locking the frame against pivotal movement, means for automatically locking the arms in embrace with the pouch as the latter passes therebetween, 100 and means thereafter unlocking said frame, whereby it is adapted to swing on its pivot.

12. In a mail pouch receiver, a pivotally supported lever, bars pivoted to said lever, a pouch-embracing arm pivoted to both of said 110 bars, a second pouch-embracing arm pivoted to one of said bars, and a link pivotally connecting the other of said bars with the last-named arm.

13. In a mail pouch receiver, a lever, bars pivoted to said lever, a pouch-embracing arm pivoted to said bars, a second pouch-embracing arm coacting with the first pivoted to one of said bars, a link connecting the other of said bars with the last-named arm, and 115 means attached to said link adapted to engage with said lever and lock said arms when they approach each other.

14. In a mail pouch receiver, a lever, bars pivoted to said lever, a pouch-embracing arm pivoted to both of said bars, a second pouch-embracing arm coacting with the first and pivoted to one of said bars, a link connecting the other of said bars with the last-named arm, a spring-arm carried by said link for en- 120 125 130

gaging said lever and locking said arms when they approach each other, a locking lever for locking the first-named lever against movement, and means adapting said lever to be 5 automatically unlocked by the movement of said arms.

15. In a mail pouch receiver, a support having a fixed bearing-plate provided with bifurcated opposite ends, a second bearing- 10 plate pivoted to the support in contact with the first-named plate having the opposite ends thereof likewise bifurcated, a frame pivoted to the pivoted bearing-plate having pouch-embracing arms, and a locking lever 15 operating within the bifurcations of said plates for locking the arms at either side of said support.

16. In a mail pouch receiver, a support, a frame connected with said support adapted 20 to be swung in a substantially horizontal and in a vertical plane, arms for embracing the pouch forming a part of said frame, means for locking the frame to either side of said support, whereby the direction of said arms 25 may be reversed, and means for locking said arms when they approach each other.

17. In a mail pouch receiver, a support, a plate having extensions provided with angular extremities carried by the front of said 30 support, a bearing-plate fixed at the opposite side of said support, a second bearing-plate revoluble in a substantially vertical plane with respect to the first-named bearing-plate, a frame pivoted to the revoluble bearing- 35 plate having pouch-embracing arms, means

for locking the said plates together when the frame is disposed in a substantially horizontal position, and a locking lever forming an element of said frame adapted to alternately engage with the angular extremities of the 40 first-named plate when the frame is disposed at the opposite sides of the support.

18. In a mail pouch receiver, a lever, bars pivoted to said lever, a pouch-embracing arm pivoted to said bars, a second pouch-embracing arm pivoted to one of said bars, a link connecting the other of said bars with the last-named arm, a bearing-plate carried by the link, and a spring-arm connected with said link and passing through said bearing-plate adapted to engage with said lever and lock said arms as the arms are brought together.

19. In a mail pouch receiver, a support, a frame pivoted to said support adapted to swing in a substantially horizontal plane and having arms for embracing the pouch, and means adapting said frame to be revolved in a substantially vertical plane on said support, whereby the said arms may be reversed 55 and directed in opposite directions at the 60 opposite sides of said support.

In testimony whereof I have signed my name to this specification in the presence of two subscribing witnesses.

OLIVER FISHER.
